UNITED STATES PATENT OFFICE.

ROBERT H. PLASS, OF UPPER MONTCLAIR, NEW JERSEY, ASSIGNOR TO POLORIS COMPANY, INC., OF NEW YORK, N. Y., A CORPORATION OF NEW YORK.

PACKAGING MACHINE.

Application filed February 26, 1926. Serial No. 90,921.

This invention relates more especially to packaging machines in which cartons in a collapsed condition are fed one by one from a source of supply to a conveyor which presents said cartons to a succession of mechanisms whereby said cartons are set up, charged, closed, and stacked.

The primary object of this invention is to provide an improved construction for machines of this character whereby certain desired operations connected with the preparation, charging and closing of cartons, may be performed in an improved manner in connection with a substantially continuous supply of the articles to be packaged for distribution.

Another object of invention is to provide an improved construction, combination, and arrangement of parts in each of said mechanisms which are thereby adapted to cooperate with the carton-conveyor during successive periods of rest.

Other and further objects of invention will appear in the specification and be pointed out in the appended claims, reference being had to the accompanying drawings which illustrate a preferred embodiment of my invention and in which:—

Figure 1 is a top plan view of the preferred embodiment of my improved packaging machine;

Figures 2 and 2^a constitute an enlarged vertical section of the machine on the line 2—2^a, Figure 1, parts being shown in elevation;

Figure 2^b is an enlarged detail of Figure 2, showing the carton-shaping anvil or plunger in operative position;

Figure 3 is a horizontal section on the line 3—3, of Figures 2 and 2^a, surrounding portions of the fixed table or top plate being broken away;

Figure 4 is an enlarged top plan view of a portion of Figure 1, showing the carton-feeding and setting-up mechanism;

Figure 5 is an enlarged vertical section corresponding to the broken line 5—5, of Figure 1, parts being broken away and parts shown in elevation;

Figure 6 is a fragmentary portion of Figure 5, showing parts in changed positions;

Figure 7 is a section on the line 7—7, of Figure 4, parts being shown in elevation;

Figure 8 is a fragmentary section on the line 8—8, of Figure 4;

Figure 9 is an enlarged vertical section on the line 9—9, of Figure 1, showing mechanism for closing the flaps at one end of the carton;

Figure 10 is a horizontal section on the line 10—10, Figure 9;

Figures 11 to 16 inclusive are enlarged fragmentary sections similar to Figure 9, showing successive stages in the flap-closing operation;

Figure 17 is an enlarged top-plan view of the circular-insert mechanism, shown in Figure 1, parts being broken away;

Figure 18 is a vertical section corresponding to the line 18—18 of Figure 17, parts being shown in elevation;

Figure 19 is a vertical section on the line 19—19, Figure 18, parts being broken away and parts shown in elevation;

Figure 20 is a horizontal section on the line 20—20, Figure 18, parts being broken away and parts shown in plan;

Figure 21 is an enlarged fragmentary horizontal section corresponding to the line 21—21 of Figure 18, parts being broken away, the inner slide being in a relatively advanced position;

Figure 22 is a vertical section on the line 22—22, Figure 21, parts being shown in elevation;

Figure 23 is an enlarged vertical section of the poultice-charging mechanism, parts being broken away and parts shown in elevation;

Figure 24 is a vertical section on the line 24—24, of Figure 23;

Figure 25 is an enlarged fragmentary section on the line 25—25 of Figure 23;

Figure 26 is a horizontal section on the line 26—26, Figure 23;

Figure 27 is an enlarged vertical section of the second flap-closing mechanism, said section corresponding to the line 27—27, Figure 1 with parts broken away and parts shown in elevation.

Figure 28 is an end elevation of the same taken from the left in Figure 27;

Figure 29 is an enlarged top plan view of the carton packing and discharge mechanism shown in Figure 1, parts being broken away;

Figure 30 is a vertical section on the line

30—30, Figure 29, parts being shown in elevation;

Figure 31 is a vertical section on the line 31—31, Figure 30, parts being broken away 5 and parts shown in elevation;

Figure 32 is a section on the line 32—32, Figures 2 and 2^a;

Figure 33 is a horizontal section on the line 33—33, Figure 2 showing in top-plan 10 view the cam-movement for operating the carton-shaping plunger;

Figure 34 is a section on the line 34—34, Figure 2; and

Figure 35 is a detail in elevation corresponding to the line 35—35, Figure 30.

The present application constitutes in part, a continuation of my copending application Serial Number 6765, filed February 4, 1925.

20 For convenience in description, the drawings will be more particularly referred to in connection with the several mechanisms which are arranged to cooperate with the carton-conveyor of said conveyor.

25 *Table operating mechanism.*

Referring more especially to Figures 1, 2, 2^a, and 3 of the drawings, a lower plate 1 which is carried by uprights 2, is provided 30 with an opening 3 for the accommodation of a bearing 4 carried by an integrally-formed plate 5, said plate 5 being secured to the plate 1 around the edge of opening 3 by means of bolts 6. A power shaft 7 which 35 is journaled in a bearing 8 carried by a pedestal 9 mounted upon the plate 1, has keyed thereto a bevel pinion 10 which meshes with a bevel gear 11 keyed to a vertical cam shaft 12, the lower end of said cam shaft being 40 journaled in the bearing 4. The upper end of the bearing 4 is provided with a thrust bearing plate 13 between which and an upper bearing plate 14 are arranged suitable ball bearings 15. It will be seen from 45 Figure 2 that the bevel gear 11 is provided with a hub 16 by means of which the end-thrust on bevel gear 11 may be taken by the bearing plate 14. The upper end of the cam shaft 12 is journaled in a bearing 17 50 carried by an upper plate or table 18 which is mounted upon the uprights 2. Keyed to the upper end of the cam shaft 12, as shown in Figure 3, is a spur gear 19 which meshes with a second spur gear 20 journaled 55 upon a stud 21 threaded into the top plate 18. Threaded into the spur gear 20 near the periphery thereof is a stud 22 on which is pivotally mounted one end of a link 23, the other end of said link being pivotally 60 connected to a stud 24 carried by a lever arm 25 which swings about a stud 26 mounted in the top plate 18. The bifurcated outer end 27 of lever arm 25 engages a roller 28 journaled on a stud 29, said stud being 65 threaded into an inwardly-presented pro-

tuberance 30 of an oscillatory ring 31. As shown in Figure 2, the ring 31 rests upon the surface of table 18 and has its outer periphery in slidable contact with the inner base flange of a cylindrical housing 32, said 70 housing being rigidly mounted upon the upper plate or table 18 and constituting a supporting frame for the carton-conveyor which is now to be described. For this purpose, a cylindrical frame 33 which forms 75 a part of the carton conveyor, is provided with an outwardly-presented flange 34 which is slidably mounted in an inwardly-presented groove in the upper portion of stationary frame 32, said carton conveyor 80 being thereby supported independently of ring 31 so as not to interfere with the latter's reverse movements. Adjacent its lower edge, the traveling frame 33 is provided with a plurality of inset dog and ratchet blocks 35 85 (see Figure 3) which, as shown clearly in Figures 9, 23, and 27, are provided with upper rectangular recesses 36 and lower acute-angled recesses 37. Each of said rectangular recesses 36 is adapted to receive the squared outer end 38 of a locking dog 39 which, as shown in Figure 3, is pivotally mounted upon a stud 40 and yieldably held in locking engagement with the recess 37 by means of a spring 41. Each of the lower recesses 37 95 is adapted to receive a ratchet pawl 42 which is pivotally mounted upon a stud 43 carried by the ring 31. Said pawl is pressed outwardly by means of a leaf spring 44 so that during clockwise movements of the drive 100 ring 31, the cylindrical frame or support 33 is made to partake of its movement whereas during the counter-clockwise movements of ring 31, the ratchet pawl 42 will be dragged from the lower recess 38 and after sliding 105 along the inner wall of frame 33, will drop into the next recess 38 in the lower series. At the end of each counter-clockwise movement of the drive ring 31, a pin 46 carried thereby, will be thrown into engagement 110 with an inclined surface 45 near the outer end of locking dog 39, for displacing said dog from rectangular recess 37 and thus releasing the cylindrical support 33 to partake of the next clockwise movement of the ring 115 31, which thus imparts a clockwise movement to the carton conveyor. Referring now to Figures 2, 5 and 6, it will be seen that the traveling frame or support 33 is surrounded by a rigid castellated frame or 120 structure including raised carton-carrying plates or tables 50 which are circumferentially interposed between depressed portions 51 of the structure and integrally connected thereto by spaced uprights 52 (see Figures 125 27). Presented in opposite directions from the uprights 52 are lugs 53 which carry suitable pivots 54 for carton-gripping levers, each of said levers comprising a gripper-arm 55 provided with an elongated clamp- 130

ing jaw 56 and a lever arm 57 provided with an anti-friction roller 58. These gripping levers in their separated positions are adapted to receive between them, a collapsed carton and afterwards by the inward movement of one of them, to press upon the lateral edges of the collapsed carton and in conjunction with a plunger anvil to be herein-after referred to, to open and set up said 10 carton. According to the preferred embodiment of my invention shown on the drawings said carton is provided with flaps at both ends, the carton-conveyor being adapted to receive the cartons from a hopper 15 containing a stack of collapsed cartons for presenting them one by one in successive positions to have the flaps at one end closed, next to receive a circular thru its unclosed end, then to have the flaps at the other end closed, and finally to be removed from the 20 carton-conveyor and stacked.

25 *Carton-feeding mechanism.*

As shown in Figure 2, a hopper 59 is arranged at some distance above the upper plate 18 and presented inwardly from a triangular bracket 60 which is secured to 30 the table 18 by means of bolts 61. As shown in Figure 5, said hopper is arranged to discharge on to the raised tables 50 of the carton-conveyor. For this purpose, said hopper is provided with laterally-spaced 35 bottom plates 62 extending along opposite bottom edges thereof, a rectangular corner block 63 which is rigidly secured to a vertical plate 64 by screws 65, being extended together with the plates 62 to form suitable 40 guides for a carton-feeding slide. Thus, as shown best in Figure 7, the plates 62 constitute oppositely presented guides for the slide which comprises a lower rabbeted plate 66, an upper plate 67 riveted thereto, and a 45 bifurcated bracket 68 which carries a pin 69. Upon this pin, as shown in Figure 5, is journaled a roller 70 which operates in the slotted upper end 71 of a lever arm 72 keyed to an oscillatory shaft 73, said shaft being 50 mounted in bearings 74. A downwardly-presented lever arm 75 provided with a double bifurcated lower end 75^a, is keyed to the other end of shaft 73 and movably engages rollers 76 journaled on oppositely- 55 presented pins 76^a on a block 77 which is carried by a reciprocating cam rod 78. The outer end of said cam rod 78 is reciprocably mounted in a guide 79, (see Figures 5 and 32), its widened inner end being provided 60 with a slot 80 within which slides a guide block 81, said guide block being mounted on the cam shaft 12. As shown in Figures 2 and 5, the widened inner end of the cam rod 78 is slidably supported by the flat upper 65 surface of a cam 82 which is keyed to the

cam shaft 12 and provided with an upwardly presented cam slot 83 within which runs a cam roller 84 journalled upon a stud 85, said stud depending from the under side of cam rod 78. It will be understood from 70 Figure 4 that the cam movement thus described serves to reciprocate the carton-feeding slide which operates to discharge successive cartons from the bottom of a stack of collapsed cartons C in the hopper 60. At 75 each recurrence of this operation, one of the box-gripping lever arms is moved toward the right according to Figure 6 to permit the introduction of a collapsed box thereover on to one of the raised tables 50. Means 80 for imparting this movement to said gripper arm may be provided as follows. Mounted on the lever arm 72 is a supporting guide 72^a which carries a pusher 86 which is connected thereto by adjustable connections 87. 85 As the lever arm 72 moves toward the left according to Figure 5, the pusher 86 comes into engagement with a roller 88 journalled in the outer end of one arm 89 of a bell-crank lever which is pivotally mounted on 90 a stud bolt 90 threaded into an adjacent wall of the bracket 60. The other arm 91 of said lever carries a pad at its outer end which bears against a roller 92 journalled in the power arm 57 of the right-hand gripping 95 lever according to Figures 5 and 6. This operation serves to move said lever into the position shown in Figure 6, a coil spring 93 operating to return the lever 89, 91, to its initial position shown in Figure 5 as soon 100 as the carton-feeding slide is retracted for a new operation, whereupon the spring 55^a operating upon gripper arm 55, returns said gripper arm to normal position as shown in Figure 5. 105

Carton setting-up mechanism.

Referring to Figures 1, 2, 2^b, 4, 5, 6, 32, and 33, the carton setting-up mechanism may be taken to include in addition to the carton-gripping levers, a horizontally-reciprocal slide 94 and a cam movement for reciprocating said slide. The slide 94 is provided at its forward end with an overhanging portion 95 of enlarged cross-section and from which projects a carton-opening plunger or anvil 96. Said plunger anvil has its top and bottom faces as well as its lateral edges beveled to form a wedge 97, at its forward end to facilitate its introduction into the opening carton as the outer edges thereof are pressed inwardly by the gripping levers 55. For this purpose, each of the gripping levers 55 is provided with a coil-spring 98, said coil-springs operating to compress the opening carton around the anvil 96 as the carton-feeding slide is being retracted therefrom. As shown in Figures 2 and 4, the slide 94 reciprocates in laterally-spaced guides 99. From its under face de- 125 130

pends a bifurcated bracket 100 which carries a transverse pin 101 upon which is journalled an anti-friction roller 102. Depending from the under face of table 18, is a bracket 103 which carries a stud 104. Pivotally mounted upon this stud is a lever comprising an upwardly-extending arm 105 and a downwardly-extending arm 106, said upper arm 105 being provided with a slotted 10 upper end 107 movably engaging the roller 102. The depending arm 106 is provided with a slotted lower end 108 which movably engages a roller 109 journalled upon a pin 110 carried by a collar 111 which is adjustable lengthwise on a cam rod 112. Said cam rod which has its outer end reciprocably mounted in a bracket 113 depending from the underside of table 18, is provided with a flattened inner end 114 slidably supported 20 by the upper surface of a cam 115. Depending from the underside of rod end 114 is a stud 116 upon which is journalled a cam roller 117 that operates in cam slot 118 of the cam 115. The inner end of cam rod 112 is provided with a longitudinal slot 119 within which slides a block 120 on the cam shaft 12.

Flap-closing mechanism.

30 Referring now to Figures 9 and 10, stud-bolts 125 which extend thru the table 18, are threaded into the base portion of a bracket 126. Secured to the inner vertical face of bracket 126 and projecting upwardly 35 thereabove, are laterally-spaced uprights or supports 127 which are provided with parallel bearing lugs 128 for a cam-shaft 129, said cam-shaft receiving its power from vertical cam-shaft 12. As shown in Figure 3, the 40 gear 19 which is keyed to cam-shaft 12, meshes into a spur gear 130 which is keyed to the lower end of a vertical shaft 131. As shown in Figure 2, the lower end of shaft 131 is journalled in table 18, the upper end thereof being journalled in a bent bracket 132 carried by one of the uprights 127 as shown in Figure 10. Keyed to the upper 45 end of shaft 131, is a bevel gear 133 which meshes with a bevel gear 134 keyed to one end of the cam-shaft 129. Keyed to the 50 other end of shaft 129, is a cam 135 provided with a cam groove 136 within which travels a cam-roller 137 journalled on a stud 138, said stud projecting laterally from a 55 slide 139 which is reciprocably mounted in the adjacent upright 127. The slide 139 is provided at its outer end with a laterally-slotted end 140 which engages a roller 141 journalled on a stud 142 depending from a 60 lever arm 143. Projecting outwardly from the uprights 127 and having their outer ends deflected toward each other, are two bracket arms 144 which carry in their outer ends suitable studs 145 for oscillatably 65 supporting the hub portions 146 of two oppo-

sitely arranged hook-shaped anvil-levers 147. As shown in Figures 11 to 16 inclusive, the anvil-levers 147 are provided with a wedge-shaped cross section with flattened top surfaces 147^a, said levers being tapered towards 70 their outer ends and movable into and out of position to have the long wide flaps of the cartons bent over and around the triangular section of said levers preparatory to inserting the end of said flaps into a carton. In order to constrain these anvil-levers to move in unison, each hub-portion 146 carries a gear sector 148, these gear sectors being in mesh with each other so that as the slide 139 reciprocates, the anvil-levers 147 75 are moved to and fro between the positions indicated in full and dotted lines on Figure 10. Oscillatably mounted upon a transverse shaft 149, is the hub 150 of a pusher frame which includes laterally-spaced lever-arms 151 provided with bifurcated upper ends 152. One of said lever-arms carries a laterally-presented stud 153 upon which is journalled a cam-roller 154 which runs on a cam 155 keyed to the cam-shaft 129 where- 80 by the pusher frame is moved to and fro. Referring more especially to Figures 10 to 16, the inner face of each of the uprights 127 is provided with a horizontal groove 156 within which slides a rectangular bearing 85 block 157. Extending between these bearing blocks 157, is a transverse shaft 158 about the axis of which oscillates a lever comprising a cam-arm 159 and a pusher arm 160. Journalled on a stud 161 which projects laterally from cam-arm 159, is a cam-roller 162 which runs on a three-stage cam 163 keyed to cam-shaft 129 and comprising an inner run 163^a (see more especially Figures 11 and 12), an outer run 163^c, (see 90 more especially Figure 16), and an intermediate stage 163^b (see more especially Figures 13, 14, and 15). Referring now to Figures 11 to 16 inclusive, the pusher arm 160 is provided with a depending lug 164 to which is pivotally connected one end of a flap-turning blade 165. Secured at one end to the top face of the pusher arm 160, is a bent leaf-spring 166, a link-pin 167 depending therefrom thru an aperture in the pusher arm 160, and supportably engaging the blade 165. This device provides a yieldable suspension for the blade 165 and normally tends to retain said blade in contact with the under surface of arm 160 but permits said blade to be depressed by the beveled under surface of the anvil-levers when the end of said blade is caused to travel thereover. The outer end of the pusher arm 160 is widened and curved upwardly as 110 shown in Figures 9 and 11 to 16 inclusive to provide a flap-wiper 160^a which is adapted to depress the bent flap and shove it into the carton. Projecting upwardly from the pusher lever is a lug 168 to which is con- 115 120 125 130

nected one end of a tension coil spring 169, the other end of said spring being connected to the downwardly deflected end of a bracket arm 170 (see Figure 9). The operation of the flap-closing mechanism will now be readily understood from an inspection of Figures 9 to 16 inclusive.

With the parts in their relative positions shown in Figure 9, the cam roller 162 carried by cam-arm 159, is traveling over the inner run 163^a of the three-stage cam 163 while the cam-roller 154 on the vibratory frame 151 is traveling over the inner run of cam 155. At the same time, the cam-roller 137 carried by the slide 139 is moving over the inner run of cam 135. Under these conditions, the continued rotation of cam-shaft 129 serves to throw the vibratory frame toward the left according to Figure 9 while 20 the slide is operated in the same direction to throw the anvil-levers 147 inwardly toward dotted line position shown in Figure 10. Said anvil-levers are thus moved from their positions indicated in Figure 11 to their 25 positions shown in Figure 12 whereupon the successive runs of the three-stage cam 163 oscillates the pusher-lever 160 upon its axis to throw the blade 165 downwardly against the main flap which overhangs the 30 anvil-levers in their inner positions and thus serving to depress said flap about the sharp edge of the anvil-levers as shown in Figure 13. Thereupon, as the oscillatory frame continues its forward movements, the flap 35 bending blade 165 deflects the bent-over end of said flap around the anvil-levers into the position shown in Figure 14 whereupon the slide 139 being retracted toward the right, returns the anvil-levers to full-line positions 40 shown in Figure 10 whereupon the wiper blade 160^a, moving downwardly, depresses the bend in the flap while the blade 165 guides the free end thereof into the carton as indicated in Figure 15. In its lowermost 45 position shown in Figure 16, the wiper 160^a has moved the main flap into its final position. Prior to this however, the initial inward movements of the anvil-levers 147, have folded the smaller lateral flaps inwardly as indicated in Figure 12.

Flap-retaining means.

Referring more especially to Figures 1, 2^a, 4, 9, 17, 22, it will be understood that 55 during the successive operations for closing the flaps at one end, charging a circular into the carton thru the other end, and for charging the articles into the carton, it is necessary to hold the main flap at the open 60 end of the carton in a position in which these operations will not be interfered with. For this purpose a part-circular guide or guard is arranged outside of and extending around the path of the carton-carrying tables of the 65 carton-conveyor, said guide or guard extend-

ing from the carton-setting-up mechanism to the mechanism for closing the flaps at the open ends thru which the cartons have been charged. As clearly shown in Figure 22, the part-circular flap-guide comprises an 70 arcuate bottom plate 171 and an arcuate top plate 172 of relatively great width, spaced from each other by an interposed arcuate plate 173, of relatively small width to form an inwardly-presented slot 174.

As shown in Figures 1 and 17, the part-circular flap-guide is supported by suitable brackets 175 having their base-flanges secured to table 18 and their top flanges secured to the underside of said flap-guide. 80 It will be seen by an inspection of Figure 22 that the flap-guide is disposed slightly below the level of the carton-supporting tables and at slight inclination with respect thereto to keep the flap out of the way of instruments 85 operating to introduce the circulars and poultices thru the open ends of said carton.

Circular-insert mechanism.

By an inspection of Figure 1, it will be seen that the next operation in order after closing one end of a carton, is the insertion of a circular into the other end thereof. The circular-insert mechanism may be readily understood in connection with Figures 2^a, 17, 18, 20, 21 and 22. Referring to Figure 2^a, a power shaft 177 which is journaled in bearings 178 carried by bracket 179 which depends from the under side of table 18, carries a bevel pinion 180 which meshes with a bevel gear 181, said gear 181 being keyed to the lower end of a vertical shaft 182 indicated in dotted lines in Figure 17. As indicated in dotted lines in Figure 17, 105 the upper end of shaft 182 has a worm 185 keyed thereto and meshing into a worm gear 186, said worm gear being keyed to a horizontal shaft 187 which is journaled in bearings 188 and 189. A miter gear 190 which is keyed to the other end of shaft 187 meshes into a second miter gear 191 keyed to a shaft 192 which is journaled at opposite ends in bearings 193 and 194. Referring now to Figures 18 and 20, the shaft 192 has keyed thereto a cam 195 over which travels a cam roller 196 journaled upon a stud 197 carried by the strap end 198 of a rod 199 which is pivotally connected at its other end by a pin 200 to an oscillatory crank arm 201 which is pivotally mounted upon a cross-shaft 202. A spring 203 exerts pressure on the lever arm 201 in such a way as to hold the cam roller 196 in contact with the cam 195. A guide block 204 is mounted upon the shaft 192 in slidable engagement with the walls of a longitudinal slot 205 with which the strap 198 is provided for constraining the movements of that end of the rod under the action of cam 195. The upper end of 130

crank arm 201 is provided with a slot 206 within which operates a roller 207 journalled upon a pin 208, said pin being carried by laterally spaced bearing lugs 209 which depend from opposite edges of a channeled slide 210. Said roller 207 is spaced from the bearing lugs 209 by collars 211. Secured to the left end of slide 210, according to Figure 18, is a flattened box-like receptacle 212 which as shown in Figures 21 and 22 is provided at its inner end with a narrow discharge opening 213, said opening being formed by inwardly contracted top and bottom portions of the walls of said receptacle. The lateral dimension of said receptacle is also contracted by an inward displacement of the edge walls 214 of said receptacle to facilitate its introduction into the open end of a carton C presented thereto by the carton-conveyor after one of its periodic movements. As shown in Figure 17, the receptacle 212 is provided with laterally presented tabs 215 secured to the forward end of slide 210 by screws 216. The slide 210 is provided with a central longitudinal opening 210^a and is carried by laterally-spaced slides 217 which reciprocate in grooves 217^a in side frames 227. A plate 218 secured to slides 217, forms therewith a guideway for an inner slide 219. The forward end of slide 219 is provided with projections 220 as shown in Figure 21, said projections being adapted to engage the rear edge of a folded circular S for propelling it thru the outlet 213 of receptacle 212 and for retaining said circular within the carton C during the withdrawal of said receptacle. In order to accommodate the projections 220 and to permit them to project beyond the forward end of the box-like receptacle 212, the inwardly contracted walls of said receptacle, are provided with slots 221, thus permitting the full retraction of the receptacle from the carton before the inner slide 219 is withdrawn therefrom. As shown in Figure 18, the slide 219 is provided on its under side with a rack 222 into which meshes a floating gear pinion 223 carried by a transverse shaft 224 journalled in bearing blocks 225, said blocks being slidable in longitudinal grooves 226 formed in the side frames 227. Interposed between the blocks 225 and similar anti-friction rollers 228 carried by shaft 224 on opposite sides of pinion 223, are spacing collars 229. The rollers 228 operate in slots 230 in the outer ends of laterally-spaced crank arms 231 which project upwardly from an elongated hub 232 journalled upon a cross-shaft 233 mounted in the side frames 227. Keyed to the cross-shaft 192 is a second cam 234 over which runs a cam roller 235 journalled upon a stud 236 projecting from the strap end of a rod 237, said strap end being provided with a longitudinal slot within which is disposed a guide

block 238 carried by shaft 192. The forward end of cam rod 237 is pivotally connected to a stud 239 which projects laterally from one of the crank arms 231, the cam roller 235 being retained in running contact with the cam 234 by means of a spring 240 which exerts a pressure on the other crank arm 231 for this purpose. Arranged below the floating pinion 223 and meshing therewith is a fixed rack 241 over which said floating pinion travels with a cycloidal movement which imparts to the slide 219 a movement due to the rotation of said pinion, increased by the distance traveled by the axis of said pinion.

The operation of this mechanism may now be readily understood and briefly described as follows:—

Suitable mechanism for feeding off circulars from a pile, for folding said circulars, and for feeding the folded circulars to the above described circular-insert mechanism, is indicated as a whole in Figure 17 by the reference character 250. As here represented, this mechanism constitutes an organization of parts substantially similar to that shown in Figures 1 and 7 of the drawings in my copending application Serial Number 6,765 filed February 4, 1925. According to the present application, this mechanism 250 delivers a folded circular to the bottom slide 210 immediately in front of the projections 220 of inner slide 219. The forward movement of slide 210 under the control of cam 195, is accompanied by the more rapid forward movement of slide 219 under the control of cam 234, the net result of these forward movements being to deliver the circular S within carton C in the position shown in Figures 21 and 22. At this time, the retracting movement of receptacle 212 has already begun as indicated by the forms and relative positions of cams 195 and 234 as shown in Figures 18 and 20. During the retracting movement of receptacle 212, the rear edge of the circular C is engaged by projections 220 of slide 219 and hence remains behind within the carton C. The inner slide 219 is then withdrawn from the carton after which the next periodic movement of the table conveys the carton into position to receive the poultices or other articles to be charged thereinto.

Poultice charging mechanism.

Referring now to Figures 1 and 2^a, an endless chain conveyor comprising links 260 provided with projecting lugs 261 passes about a polygonal drum 262 carried by a shaft journalled in a bracket 263. Suitable means for driving this endless chain conveyor may be provided as follows. A power shaft 477 which is journalled in bearing brackets 478 and 479, carries a bevel pinion 480. Meshing with the bevel pinion 480 is a

- bevel gear 481 which is keyed to a short vertical shaft 482 journalled in a bearing 483 carried by a bracket arm 484 which projects laterally from the bearing bracket 479.
- 5 Keyed to the upper end of the short vertical shaft 482 is a large spur gear 485, said spur gear being in mesh with a small spur gear 486 (see dotted lines in Figure 2^a), the small spur gear being keyed to the lower end of a vertical shaft 487. Keyed to the upper end of vertical shaft 487 is a bevel pinion 488 which meshes with bevel gear 489, said bevel gear 489 being keyed to the short horizontal shaft 490 which carries the polygonal drum 15 262. The lower run of said conveyor travels thru a chute 264 which terminates adjacent to a reciprocable carrier tray or chute 265 said carrier tray being provided with laterally projecting pins 266 which are movably engaged by the bifurcated ends 267 of lever arms 268. Said lever arms are keyed to a rock shaft 269 which is journalled upon a fixed axis in laterally spaced frames. A crank arm 270 which is also keyed to said 20 25 rock shaft, carries a wrist pin 271 to which is pivotally connected the upper end 272 of a rod 273. Said rod is provided at its lower end with a strap 274 journalled upon an eccentric disk provided with a hub 275 keyed to power-shaft 477. A lever arm 276 which is keyed to rock shaft 269 and provided with a bifurcated outer end 277, movably engages the oppositely presented pins 278 carried by a vertical slide 279, said slide being provided 30 35 with serrations 280 at its lower end which, in the positions of the parts shown in Figure 2^a, are disposed immediately over a forwardly-presented shelf 265^a on the reciprocatory tray 260. The operating connections 40 45 for this device, are such that the shaft 477 rotates once during the time that the conveyor 260 travels the distance between two successive lugs 261, the result being that each reciprocatory tray 265 during its movement 50 55 away from the carton-conveyor and over its upper run, has deposited therein a group of poultices as shown in Figure 2^a. Each of said poultices is depressed by a downward movement of plunger 279 as the shelf 265^a is moved from under it.
- As shown in Figure 24, a pair of laterally spaced side frames 281 are secured to the plate or table 18 by means of bolts 282, said side frames being provided with dove-tail 55 60 guides 283 within which are reciprocably mounted slides 284, each of said slides being provided with end lugs 285. Laterally projecting studs 286 carried by the end lugs 285, serve to journal rollers 287, said rollers being adapted to travel to and fro in slots 288 formed in the upper ends 289 of cam-operated levers 290. The lower ends of said levers 290 are provided with slotted ends 291 within which are adjustable studs 292 mounted in the outer end of laterally spaced

links 293 which are pivotally mounted upon the oppositely presented ends of a bolt 294 carried by a bracket 295 on the bottom-plate 1. Secured to the under side of table 18 are a pair of depending brackets 296 provided with bearings 297 at their lower ends. Reciprocably mounted in said bearings 297 are an upper cam rod 298 and a lower cam rod 299, the former having an enlarged end 300 (see Figure 34) provided with a longitudinal slot 301 within which is disposed a guide block 302 on the vertical cam-shaft 12. Journalled upon a depending stud 303 is a cam roller 304 which travels in a cam slot 305 in the upper face of a cam-disk 306. The cam-disk 306 is keyed to the cam-shaft 12 and slidably supports the cam rod 298 on its upper surface. Arranged below the cam 80 85 90 95 100 105 110 115 120 125 130 306 and keyed to the cam-shaft 12 is a similarly formed cam 307 (see Figure 2) provided with a cam groove 308 (shown in dotted lines in Figure 34). A cam roller 309 journalled upon a stud 310 travels in the cam groove 308, said stud 310 being carried by the widened end 311 of lower cam rod 299. By an inspection of Figure 34, it will be seen that the cam grooves 305 and 308 are adapted to impart substantially similar movements to cam rods 298 and 299, these movements, however, being displaced one with respect to the other in an amount corresponding to 180 degrees of cam travel. Bolted to the cam rods 298 and 299, are blocks 312 and 315 which carry studs 313 and 316 which pivot in levers 290. It will be understood from this description that the slides 284 have similar cycles of movement whereby they are alternately engaged in charging cartons presented by the carton-conveyor.

Referring now to Figures 23 and 24, bolted to each of the dove-tail slides 284, is a base plate 318 which carries axially spaced cylindrical housings 319 within which are arranged compression springs 320, a buffer disk 321 being interposed between one end of each spring and a ball 322 which is thereby yieldably retained in one or another of vertically spaced recesses 323 formed in the outer wall of a box-like housing 324 which is rigidly secured to a plunger bar 325. As shown in Figure 26 the plunger 325 is provided with a dove-tail slide 326 by means of which it is reciprocably mounted between vertical guide plates 318. Plunger 325 carries a stud 441 upon which is journalled a roller 442 arranged to be engaged by a fixed side bar 443 to positively limit the upward throw of plunger 325. Each of the plungers 325 carries at its upper end a forwardly-presented arm 327 which carries at its forward end a charging tray 328, the charging trays being offset from their respective plungers and adapted to move into and out of a carton presented in position to be charged by the carton-conveyor. For this purpose, suit-

able means are provided to adapt said charging trays to pass one under the other on their carton-charging movements. The poultices which may have been severed from a continuous stock as shown and described in my above-identified copending application Serial No. 6,765, are made of a length which is slightly greater than the inside width of the loading trays 328 so that as said poultices 5 are forced into said loading trays, they become firmly lodged as indicated in Figure 25. The lower end of each plunger 325 carries a stud 329 upon which is journalled a cam roller 330, said cam roller being adapted 10 to 15 near the end of its movement toward the right according to Figure 2^a to be brought into engagement with an inclined cam surface 331 whereby the charging tray is depressed from the position shown in Figure 20 25 30 23, the oppositely arranged balls 322 being removed to the upper recesses or sockets 323. In the depressed portion of one charging tray, a free passageway is left open for the withdrawal of the other charging tray. As 25 shown in Figure 2^a, the forward movement of the lowered tray, causes its cam roller 330 to travel over a cam surface 332 in such a way as to again elevate the plunger 325 and bring the tray into position to enter the car- 30 ton as shown in Figure 23.

Mechanism for transferring poultices from charging trays to cartons.

As shown in Figure 24, oppositely arranged bracket arms 333 are provided with 35 terminal bearings 334 within which is oscillatably mounted a rock-shaft 335. Keyed to said rock-shaft is the hub portion 336 of a stop-arm 337 provided at its lower end with 40 a transverse bar 338 which approximately covers the cross-sectional area of each of the charging trays 328. Keyed to the outer ends of the rock-shaft 335 are disks 339 provided with peripheral recesses 340 into which balls 45 50 55 60 65 341 are adapted to seat for retaining the parts in adjusted positions. Each of said balls is mounted in a cylindrical chamber within a housing 342, a buffer disk 343 being interposed between said ball and a compression spring 344 which exerts a tendency 60 to retain said ball in either of the recesses in which it may be disposed. Keyed to the rock-shaft 335 are laterally spaced arms 345 to which are pivotally connected the inner 65 ends of connection rods 346, the other end of each of said rods being pivotally connected to a lever arm 347 (see Figure 2^a) which is oscillatably mounted upon a stud 348 carried by a bracket arm 349 which projects upwardly from either side frame. Adjustably mounted on each of the connection rods 346 are spaced stops 350 which are adapted to be engaged by an offset projection 351 carried by one or the other of the horizontal arms 327 at the upper end of plunger 325. It will

be understood from this description that at the end of the forward movement of a charging tray 328, the projection 351 carried thereby will engage the forward stops 350 and draw the stop-arm 337 into position to bar 70 the removal of poultices from the carton during the withdrawal of said charging tray. At the end of its return movement, the projection 351 will engage the outer stop 350 and thus swing the stop-arm 337 away from 75 the open end of the carton, the disk 339 being at the same time moved in a counter-clock-wise direction until the ball 341 enters into the lower recess 340. Journalled within the side frames is an oscillatory shaft 354 80 which carries an angular circular-retaining finger 352, said finger being adapted to be swung about the axis of shaft 354 into and out of engagement with the circular in the carton for retaining it in position within a 85 carton during the charging operation. About the shaft 354 is a coil spring 353 which exerts a tendency to hold the bent finger 352 in raised position. It will be understood from this description, however, that as either of the charging trays 328 moves toward the left according to Figure 23, it will slide over said finger 352 and thus depress it into circular-engaging position as shown in Figure 23. Afterwards when the 90 stop-arm 337 has been withdrawn from the carton and the tray 328 has moved toward the right, the finger 352 is released to swing upwardly and away from said carton which is thus left free to be moved by the carton-conveyor into position to have the flaps at the open end folded into carton-closing position.

Second flap-closing mechanism.

Referring to Figure 1, it will be seen that the next periodic movement of the carton conveyor which takes place after the carton has been charged, will convey the charged carton into position to have the flaps at the open end of the carton closed. The mechanism employed for this purpose may be made substantially similar to that shown in Figures 9 to 16 inclusive. In the second flap-closing mechanism, however, the parts are arranged in inverted order with respect to similar parts of the first flap-closing mechanism. This inversion of the parts is due to the fact that the main broadside flap at one end of the carton is hinged on the opposite side of the carton to that upon which the corresponding flap at the other end is hinged. As shown in Figure 2, a gear 360 which is arranged coaxially with the spur gear 20 and keyed to the shaft 21 which carries spur gear 20, meshes with an idler gear 361 which is journalled on a stud 362 which depends from the plate 18 as indicated in dotted lines in Figure 1. Meshing with the gear 361 is a second idler 363 which 125

in turn meshes with a spur gear 364 which is keyed to a vertical shaft 365, said shaft extending thru the plate 18 and carrying the gear 364 at its lower end. The upper 5 end of the shaft 365 is journalled in a bearing 366 as shown in Figures 27 and 28, said bearing being carried by a bracket arm 367 which projects laterally from an upright frame 368 which is mounted upon the base-
 10 plate 18. A miter gear 369 keyed to the upper end of shaft 365 meshes with a second miter gear 370 which is keyed to one end of a horizontal cam shaft 371. A cam 372 keyed to shaft 371, is provided with a cam-
 15 groove 373 in the inner lateral face thereof, a cam roller 374 operating therein being journalled upon a stud 375 carried by a slide 376. At its outer end, the slide 376 is provided with a socket 377 within which is ar-
 20 ranged a cam roller 378 carried by a lever-
 arm for operating sector gears 379 similar to those of the first flap-closing mechanism shown in Figure 10. Anvil levers similar to those shown in Figure 10 are operated in
 25 unison by sector gears 379 as in the first flap-closing mechanism. As shown in Figure 28, a pair of laterally spaced bearing blocks 380 are slidably mounted in grooves 381 for reciprocably supporting a trans-
 30 verse shaft 382 upon which is oscillatably mounted the elongated hub portion 383 of a pusher lever which comprises a cam-arm 384 and a pusher-arm 385. The pusher-lever is operated by a three-stage cam 386 of
 35 similar construction to that employed in the first flap-closing mechanism. Thus, a flap-bending blade 387 is adapted to bend the long flap about the anvil-levers in their inner positions, said anvil-levers on their inward movements, being adapted to fold the short flaps preparatory to the insertion of the main flap. The outer end of said pusher-lever 385 is provided with a wiper blade 388 which operates to close the main flap
 45 in the manner already pointed out in connection with the first flap-closing mechanism. Projecting from the frame 368 is a bracket arm 389 to which one end of a coil spring 390 is connected, the other end of
 50 said coil spring being connected to a lug 391 carried by the pusher 385 for holding the cam roller 386 in contact with cam 386. As shown in Figure 28, a cross-shaft 392 is carried by the uprights 368, the elongated hub
 55 393 being oscillatably mounted upon the shaft 392 by the said uprights 368. Depending from the hub 393 are laterally spaced arms 394 provided with bifurcated lower ends 395 which movably engage cam rollers
 60 396 carried by the cross-shaft 381 upon which the pusher-lever 385 is mounted. A cam roller 396 journalled upon a stud 397 which projects laterally from one of the lever arms 394, travels over a cam 398 for re-
 65 ciprocating the pusher-lever 385 towards

and away from the carton-conveyor. The operation of this mechanism being substantially similar in construction and operation to that shown in Figures 9 and 10, requires no further description.

70

Stacking mechanism.

By referring to Figures 30 and 32 of the drawings, it will be seen that the cam-shaft 12 carries a cam 400 which is provided in its upwardly-presented face with a cam groove 401 within which travels a cam roller 402 journalled upon a stud 403, said stud depending from the bifurcated strap end 404 of a cam rod 405. The strap end 404 of said cam rod is slidably supported by the upper face of the cam 400 a guide block 406 being mounted upon cam-shaft 12 and within a slot 407 in the end 404 of said rod for constraining the movement of the rod at 85 that end. The other end of cam-rod 405 is reciprocably supported by a bracket-arm 407 which depends from the underside of plate 18. By referring to Figure 1 of the drawings, it will be seen that the top plate 18 is provided with a rectangular opening 408 at opposite ends of which are arranged suitable bearings 409 and as shown in Figure 32, said bearings are provided with flanges 410 whereby they are secured by 90 means of bolts 411 to the underside of said plate 18. Mounted in the bearings 409, is a cross-shaft 412 upon which is oscillatably mounted the elongated hub 413 of a double lever-arm 414 (see Figure 30). Adjustably mounted upon the cam-rod 405 is a block 415 which fills the space between the laterally spaced bearings 416 at the lower extremities of lever-arm 414. The connection block 415 is provided with oppositely presented trunnions 417 which oscillate within the bearings 416 and thus serve to pivotally connect the rod 405 with the bifurcated bearings 416. Referring more especially to Figures 30 and 31, it will be seen that the horizontal shaft 412 has keyed thereto within the bearings 409, the hub portions 418 of two upwardly-presented lever-arms 419, the upper ends of said arms 419 being provided with laterally presented studs 420 to which 100 are pivotally connected at one end laterally-spaced links 421. The other end of each of said links is pivotally mounted upon a stud 422 which is threaded into the adjacent end of a cross-head 423, said cross-head being 105 reciprocably mounted upon laterally spaced track-bars 424 carried by the upper extensions 425 of said frames 426. As shown in Figure 30, the cross-head 423 depends below the track-bars 424 so that its path of movement is adapted to bring it into engagement with one end of a carton C presented by the conveyor at that point. As the cross-head 423 is moved toward the right according to Figure 30, the other end of 110

115

120

125

130

said carton comes into engagement with an upwardly inclined surface 427 on the enlarged outer end 428 of a detent lever 429, the carton being tilted upwardly by said inclined surface. The detent lever 429 is pivoted on a pin 430 and provided with an oppositely projecting arm 431 to which is connected one end of a coil spring 432, the other end of said coil spring being connected to a pin 433. Said spring is adapted to yieldably retain the detent lever in the position shown in Figure 30 but as the carton C continues its movement, the forward end thereof slides upwardly along the vertical surface of a pre-arranged carton which is confined between laterally-spaced guides 426 and a top plate 434, said top plate being yieldably depressed by springs 435 which are interposed between said plate and the enlarged outer ends 436 of studs 437 mounted in the extensions 425. Near the end of its upward movement, the forward end of the carton C is wedged into the angular space between said pre-disposed carton and the inclined lower edges 438 of oppositely arranged inclined blocks 439 which are secured to the extensions 425 of side frames 426. The effect of this movement is to impart a lateral displacement to the pre-disposed carton, the rear end of carton C being forced up the incline 427 and dropping into position behind the wedged-shaped end 428 of said detent lever 429. This operation is repeated as successive cartons are operated upon in the same way.

As shown best in Figures 30 and 35, a cam 440 is arranged in the path of travel of cam rollers 92 and 58 carried by carton-gripper cam arms 57, 57. In consequence when each of the carton-carrying tables reaches discharging position, the upward displacement of cam-rollers 92 and 58, produces a relaxation in pressure exerted by the carton grippers upon the carton at that point and thus facilitates the discharge of said carton.

The operation of the entire machine is obvious from the foregoing specification.

I claim:

1. In a machine of the character described, the combination with a carton-conveyor, of a hopper for collapsed cartons, a reciprocable slide for feeding said cartons one by one from said hopper on to said conveyor, said conveyor being provided with a pair of cooperating gripper jaws, a cam-operated lever for reciprocating said slide, a bumper mounted on said cam-operated lever, a bell crank lever arranged to be engaged by said bumper for imparting a relative movement of one of said gripper jaws with respect to the other to admit a collapsed carton and compressing said carton laterally, and an anvil movable into and out

of position to cooperate with said gripper jaws for opening up said carton.

2. In a machine of the character described, the combination with a carton-conveyor, of a hopper for cartons, a reciprocable slide for feeding said cartons one by one from said hopper on to said conveyor, said conveyor being provided with a pair of cooperating gripper jaws, means for operating said slide and imparting a relative movement of one of said gripper jaws with respect to the other to admit a carton, anvil-levers movable over the end tabs for folding said tabs inwardly, and means for folding the main flaps about said anvil-levers and inserting said flaps into the ends of said carton.

3. In a machine of the character described, the combination with a carton-conveyor, of a hopper for cartons, a reciprocable slide for feeding said cartons one by one from said hopper on to said conveyor, said conveyor being provided with a pair of cooperating gripper jaws, means for operating said slide and imparting a relative movement of one of said gripper jaws with respect to the other to admit a carton, anvil-levers movable over the end tabs for folding said tabs inwardly, transversely-movable blades for folding the main flaps about said anvil-levers, pusher-levers for inserting said flaps into the ends of said carton.

4. In a machine of the character described, the combination with a carton-conveyor, of a hopper for cartons means for operating a reciprocable slide for feeding said cartons one by one from said hopper to said conveyor, said conveyor being provided with a pair of cooperating gripper jaws means for operating said slide, anvil-levers movable over the end tabs of a carton for folding said tabs inwardly, and means for folding the main flaps about said anvil-levers and inserting said flaps into the ends of said carton.

5. In a machine of the character described, the combination with a carton-conveyor, of a hopper for cartons with inner tabs and a main flap at each end, means for feeding said cartons one by one from said hopper on to said conveyor, means for charging said cartons, anvil-levers movable over said tabs to arrange them across the ends of said carton, wiper blades movable past said anvil-levers for folding the main flaps about said anvil-levers, pusher-levers for inserting said flaps into the ends of said carton, said wiper blades being oscillatably mounted on said pusher-levers, and means for oscillating said pusher-levers about movable axes.

6. In a machine of the character described, the combination with a carton-conveyor, of a hopper for cartons with inner tabs and a main flap at each end, means for

feeding said cartons one by one from said hopper on to said conveyor, means for charging said cartons, anvil-levers movable over said tabs to arrange them across the ends of said carton, vibratory frames, pusher-levers oscillatable on said frames for inserting said flaps into the ends of said carton, and wiper blades yieldably mounted on said pusher-levers for folding said flaps over said anvil-levers prior to the inserting of said flaps.

7. In a machine of the character described, the combination with a carton-conveyor, of means for feeding cartons to said conveyor, anvil-levers movable into and out of positions adjacent to the ends of said carton, wiper-blades for folding the flaps of said carton about said anvil-levers, pusher-levers for inserting said flaps into the ends of said carton, vibratory frames upon which said pusher-levers are oscillatably mounted, cam-shafts, cams keyed to said shafts for oscillating said pusher-levers, said wiper-blades being connected to said pusher-levers and cams keyed to said shafts for vibrating said frames.

8. In a machine of the character described, the combination with a carton-conveyor, of a hopper for collapsed cartons with inner tabs and a main flap at each end, a reciprocable slide for feeding said cartons one by one from said hopper on to said conveyor, said conveyor being provided with a pair of cooperating gripper jaws, means for imparting a relative movement of one of said gripper jaws with respect to the other to admit a collapsed carton and compressing said carton laterally, an anvil movable into and out of position to cooperate with said gripper jaws for opening up said carton, means for charging said cartons, anvil-levers movable over said tabs to arrange them across the ends of said carton, and means for folding the main flaps about said anvil-levers and inserting said flaps into the ends of said carton, said means comprising a vibratory frame, pusher-levers oscillatably mounted thereon, and wiper-blades connected to said pusher-levers.

9. In a packaging machine, the combination with a main frame, of a power-driven cam-shaft journalled therein on a vertical axis, a circular conveyor table coaxially arranged with respect to said cam-shaft, said table being provided with pawl and dog recesses, an oscillatory ring coaxially arranged with respect to and driven by said cam-shaft, a pawl carried by said ring and adapted to engage said pawl recesses, a dog adapted to removably engage in said dog recesses, and means carried by said ring for moving said dog out of engagement with the dog recesses.

10. In a packaging machine, the combination with a main frame, of a power-driven cam-shaft journalled therein on a vertical

axis, a circular conveyor table coaxially arranged with respect to said cam-shaft, an oscillatory ring coaxially arranged with respect to and driven by said cam-shaft, a pawl mounted on said ring for driving said table, a dog adapted to releasably engage said table, and means operated by said cam-shaft and cooperatively arranged with respect to said conveyor table for charging and closing cartons conveyed by said conveyor table.

11. In a packaging machine, the combination with a main frame, of a power-driven cam-shaft journalled therein on a vertical axis, a circular conveyor table coaxially arranged with respect to said cam-shaft, said table being provided with a downwardly-extending cylindrical flange provided with inwardly-presented pawl and dog recesses, an oscillatory ring coaxially arranged with respect to said cam-shaft, said ring having operating connections with said cam-shaft, a pawl mounted on said ring and adapted to engage the pawl recesses in said flange, a dog adapted to yieldably engage said dog recesses, and means carried by said ring for moving said dog out of engagement with the dog recesses.

12. In a machine of the character described, the combination with a conveyor provided with cooperating gripper jaws, means for imparting a yieldable pressure tending to hold said gripper jaws in carton holding position, a reciprocable slide for delivering cartons to said gripper jaws, an oscillatable lever for operating said slide, and means actuated by said lever for imparting a relative movement to one of said jaws with respect to the other of said jaws to admit a carton.

13. In a machine of the character described, the combination with a conveyor, of cooperating gripper jaws mounted thereon, one of said gripper jaws being movable relatively to the other to permit the introduction and removal of a carton, said movable gripper-jaw being provided with a depending lever arm, a reciprocatory slide for feeding cartons to said gripper jaws, an oscillatory lever for operating said slide, and a bell-crank lever suitably mounted and arranged to operate with one arm upon said depending lever arm, and having its other arm in the path of a part carried by said slide-operating lever.

14. In a machine of the character described, the combination with a rotary conveyor table, of a plurality of pairs of cooperating gripper jaws mounted thereon, one gripper jaw of each being pivotally-mounted to adapt it to move into and out of position to grip a carton between it and the gripper-jaw cooperating therewith, means for feeding cartons to said gripper-jaws, means for imparting a step by step rotation

- to said conveyor table to bring different pairs of said gripper-jaws successively into position to receive cartons from said carton-feeding means, an oscillatory lever suitably mounted and arranged to operate upon the pivotally-mounted gripper-jaw of each successive pair when in carton-receiving position, and means operated by said carton-feeding means for oscillating said lever.
- 10 15. In a packaging machine, the combination with an oscillatory power-transmitting ring, of a carton-conveying table, operating connections between said power-transmitting ring and said carton-conveying table for imparting a step-by-step movement to the latter, and means for delivering cartons to said table.
16. In a packaging machine, the combination with an oscillatory power-transmitting ring, of a carton-conveying table provided with a circular frame depending therefrom above said power-transmitting ring, and operating connections between said power-transmitting ring and said circular frame for imparting a step-by-step movement to the latter.
17. In a packaging machine, the combination with a power-driven shaft, of a power-transmitting ring, operating connections between said power-driven shaft and said power-transmitting ring, a carton-conveying table provided with a peripheral flange, a fixed frame extending around the outer periphery of said power-transmitting ring, said fixed frame being provided with a supporting guide slidably engaging said flange for supporting said table, and operating connections between said power-transmitting ring and said carton-conveying table for imparting a step-by-step movement to the latter.
18. In a packaging machine, the combination with a power-driven cam-shaft rotatable on a vertical axis, of a circular conveyor table rotatable in a horizontal plane, said conveyor table being concentrically arranged with respect to said shaft, carton-gripping means carried by said conveyor table, an oscillatory ring concentrically arranged with respect to said cam-shaft and rotary table, operating connections between said power-driven cam-shaft and said ring, power connections between said ring and said table for imparting a step-by-step rotary movement to said table, means for feeding cartons to said carton-gripping means, and operating connections between said power-driven cam-shaft and said carton-feeding means.
19. In a packaging machine, the combination with a power-driven shaft rotatable on a vertical axis, of a fixed circular frame concentrically arranged with respect to said cam-shaft, a circular conveyor table rotatably mounted in said fixed circular frame, an oscillatory ring concentrically arranged with respect to said cam-shaft and rotary table and within said circular frame, operating connections between said power-driven shaft and said ring, power connections between said ring and said conveyor table.
20. In a packaging machine, the combination with a fixed table provided with an upwardly presented circular frame, of a circular conveyor provided with a peripheral flange slidably supported in said circular frame, carton-gripping means carried by said circular conveyor, a vertical power-shaft having its upper end journalled in said fixed table, said power shaft being concentrically arranged with respect to said circular conveyor, a power-transmitting ring slidably supported by said fixed table within said circular frame, operating connections between said power-shaft and said ring, and power connections between said ring and said circular conveyor.
21. In a packaging machine, a conveyor movable about an axis and having a portion thereof concentric to said axis provided with pawl and dog recesses, an oscillatory ring coaxially arranged with respect to said axis, means for oscillating said ring about its axis, a pivotally-mounted pawl carried by said ring and adapted to engage said pawl recesses one after another, and a dog mounted on a fixed axis and adapted to engage said dog-recesses one after another.
22. In a packaging machine, a circular conveyor movable around a vertical axis, said conveyor being provided with pawl and dog recesses, an oscillatory ring coaxially arranged with respect to said axis, means for oscillating said ring about its axis, a pivotally-mounted pawl carried by said ring and adapted to engage said pawl recesses one after another, and a dog mounted on a fixed axis and adapted to engage said dog-recesses one after another, said pawl and dog being movable into and out of engagement with their respective recesses under the control of the oscillatory movements of said ring.
23. In a packaging machine, a conveyor table movable around a vertical axis, said table having a circular frame provided with pawl and dog recesses, an oscillatory ring coaxially arranged with respect to said vertical axis, means for oscillating said ring about its axis, a pivotally-mounted pawl carried by said ring and adapted to engage said pawl recesses one after another, and a dog mounted on a fixed axis and adapted to engage said dog-recesses one after another, said pawl and dog being provided with means yieldably pressing them against said circular frame and into said recesses.
24. In a packaging machine, an annular conveyor table rotatably supported with respect to a vertical axis, said table being provided with a depending frame, blocks with pawl and dog recesses mounted in the inner

wall of depending frame, an oscillatory ring coaxially arranged with respect to said annular table and below said depending frame, means for oscillating said ring about its axis, a pivotally-mounted pawl carried by said ring and adapted to engage said pawl recesses, and a dog mounted on a fixed axis and adapted to engage said dog-recesses.

25. In a machine of the character described, the combination with means for holding a carton with its main broadside flap and oppositely-arranged narrow-edge flaps presented outwardly from one end thereof, of oppositely-arranged anvil levers pivotally-mounted on laterally-spaced axes, a main-flap inserting lever, means for oscillatably and reciprocably mounting said lever, a flap-turning blade pivotally connected to said pusher lever, means for oscillating said anvil levers, means reciprocating said lever, and means for oscillating said lever.

26. In a machine of the character described, the combination with laterally-spaced supports, of oppositely-arranged anvil levers pivotally-mounted therein, oppositely-disposed slides reciprocably mounted in said supports, a vibratory pusher-frame movable between said supports, a main-flap inserting lever oscillatably mounted in said slides and movably connected to said pusher-frame and a flap-turning blade oscillatable by said lever to fold the main flap around said anvil levers and partaking of the movement of said vibratory frame.

35. 27. In a machine of the character described, the combination with oppositely-arranged anvil levers pivotally-mounted on laterally-spaced axes and movable towards each other for closing in the oppositely-arranged narrow-edge flaps of a carton, of a vibratory pusher-frame, a main-flap inserting lever oscillatably connected to said pusher-frame, a flap-turning blade yieldably connected to said pusher lever, and means for reciprocably supporting said lever.

28. In a machine of the character described, the combination with means for holding a carton with its main broadside flap and oppositely-arranged narrow-edge flaps presented outwardly from one end thereof, of oppositely-arranged anvil levers pivotally-mounted on laterally-spaced axes and movable towards each other for closing in the oppositely-arranged narrow-edge flaps, said anvil levers being provided with wedge-shaped cross-sections, a vibratory pusher-frame movable towards and away from said carton-holding means, a main-flap inserting lever oscillatably connected to said pusher-frame, said lever being provided with a rounded outer extremity adapted to movably engage the folded main flap for pressing it into said carton, a flap-turning blade yieldably connected to said pusher lever and adapted by the oscillatable movement of said

lever to fold the main flap around the edges of said anvil levers in their innermost positions and by the movement of said vibratory frame to slide along the bottom faces of said anvil levers for presenting the outer edge of 70 the main flap into position to be inserted by main-flap inserting lever.

29. In a machine of the character described, the combination with means for holding a carton with its main broadside flap and oppositely-arranged narrow-edge flaps presented outwardly from one end thereof, of laterally-spaced supports, anvil levers pivotally-mounted in said supports, said anvil levers being movable towards each other for closing in the oppositely-arranged narrow-edge flaps, and adapted in their inner positions to provide a flap-folding support, a vibratory pusher-frame, a main-flap inserting lever, means for reciprocably and oscillatably mounting said inserting lever, a pivotal connection between said lever and pusher-frame, a flap-turning blade yieldably connected to said pusher lever, and adapted to fold the main flap around the edges of 75 said anvil levers in their innermost positions, said flap-turning blade being further adapted by the movement of said pusher-frame to present the turned outer end of said main flap in position to be inserted, and means for 80 oscillating the main flap inserting lever during the movement of said pusher-frame toward said anvil levers for inserting said main flap.

30. In a machine of the character described, the combination with means for holding a carton with its main broadside flap and oppositely-arranged narrow-edge flaps presented outwardly from one end thereof, of laterally-spaced supports, anvil levers pivotally-mounted in said supports and movable towards each other to their innermost positions for closing in the oppositely-arranged narrow-edge flaps, a vibratory pusher-frame, a main-flap inserting lever oscillatably mounted and moved to and fro by said pusher-frame, a flap-turning blade yieldably connected to said pusher lever and adapted to fold the main flap around the edges of said anvil levers in their innermost positions, said flap-turning blade being further adapted by the movement of 90 said pusher-frame to present the turned outer end of said main flap in position to be inserted, and means for oscillating the main flap inserting lever during the movement of said pusher-frame toward said anvil levers for inserting said main flap.

31. In a machine of the character described, the combination with means for holding a carton with its main broadside flap and oppositely-arranged narrow-edge flaps presented outwardly from one end thereof, of laterally-spaced supports, anvil levers pivotally-mounted in said supports and mov-

able towards each other to their innermost positions for closing in the oppositely-arranged narrow-edge flaps, a vibratory pusher-frame, a main-flap inserting lever 5 oscillatably connected to said pusher-frame, and a flap-turning blade connected to said pusher lever and cooperating with said anvil levers in their innermost positions to present the turned outer end of said main flap in position to be inserted, said anvil levers being movable outwardly away from each other prior to the flap-inserting movement of said lever.

32. In a machine of the character described, the combination with means for holding a carton with its main broadside flap and oppositely-arranged narrow-edge flaps presented outwardly from one end thereof, of means for closing said flaps, said 15 flap-closing means including pivotally-mounted anvil levers mounted on laterally-spaced axes, means for moving said anvil levers towards each other for closing in the oppositely-arranged narrow-edge flaps and 20 outwardly again away from each other, a vibratory pusher-frame, a lever oscillatably connected to said pusher-frame, a flap-turning blade connected to said pusher lever and adapted to fold the main flap over said anvil 25 levers, and means for depressing said lever across the folded flap, said lever being adapted by its depression in connection with 30 the movement imparted thereto by said

pusher-frame, to tuck the main flap into said carton.

33. In a machine of the character described, the combination with means for holding a carton with its main broadside flap and oppositely-arranged narrow-edge flaps presented outwardly from one end 40 thereof, of laterally-spaced supports, anvil levers pivotally-mounted in said supports and movable towards each other for closing in the oppositely-arranged narrow-edge flaps, said anvil-levers being provided with 45 flat upper surfaces and beveled under surfaces, a vibratory pusher-frame movable between said supports, a flap-inserting lever oscillatably and reciprocably mounted in said supports and moved by said pusher-frame, said lever being provided with a curved outer extremity adapted to insert the folded main flap into said carton, a flap-turning blade yieldably connected to said 50 pusher lever and adapted to fold the main flap over the forward edges of said flat upper surfaces and to press the outer end thereof against the beveled under surfaces of said anvil levers, means for retracting said anvil levers, means for advancing said 55 pusher-frame, and means for depressing said flap-inserting lever, said flap-inserting lever being provided with a rounded upwardly-deflected extremity adapting it to wipe downwardly across said flap.

ROBERT H. PLASS.
